(57) **CLAIM**

The ornamental design for a display, as shown and described.

DESCRIPTION

FIG. 1 is a reduced scale front, right side, top perspective view of a display showing my new design;

FIG. 2 is a reduced scale front, left side, top perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a reduced scale perspective view thereof, showing a state in which plates are separated;

FIG. 10 is a partial enlarged view thereof, taken along line **10-10'-10"** of FIG. 9 and showing a state in which one of the plates is separated;

FIG. 11 is a partial enlarged view thereof, taken along line **11-11'-11"** of FIG. 9 and showing a state in which one of the plates is separated;

FIG. 12 is an enlarged perspective view of one of the plates;

FIG. 13 is an enlarged rear perspective view of one of the plates;

FIG. 14 is an enlarged front elevational view of one of the plates;

FIG. 15 is an enlarged rear elevational view of one of the plates;

FIG. 16 is an enlarged left side view of one of the plates;

FIG. 17 is an enlarged right side view of one of the plates;

FIG. 18 is an enlarged top plan view of one of the plates;

FIG. 19 is an enlarged bottom plan view of one of the plates;

FIG. 20 is a reduced scale perspective view thereof, showing a state in which the plates are removed; and,

FIG. 21 is a front elevational view thereof, showing a state in which the plates are removed.

The portions in broken lines are shown for illustrative purposes only and form no part of the claimed design. The elements are shown separately for ease of illustration only.

1 Claim, 15 Drawing Sheets
